UNITED STATES PATENT OFFICE.

JOHN A. ERICKSON, OF BROOKLYN, NEW YORK.

DESIGN FOR A COMBINATION PENHOLDER AND INKSTAND.

Application filed December 10, 1927. Serial No. 24,440. Term of patent 7 years.

To all whom it may concern:

Be it known that I, JOHN A. ERICKSON, a citizen of Sweden, residing at Brooklyn, in the county of Kings and State of New York, have invented a new, original, and ornamental Design for a Combination Penholder and Inkstand, of which the following is a specification, reference being had to the accompanying drawing, forming part thereof.

The drawing is a perspective view of a combination pen holder and inkstand embodying my design.

I claim:

The ornamental design for a combination penholder and inkstand, as shown.

JOHN A. ERICKSON.
